UNITED STATES PATENT OFFICE.

OTTO RUDD, OF KENOSHA, WISCONSIN, ASSIGNOR TO THE SIMMONS MANUFACTURING COMPANY OF KENOSHA, WISCONSIN, A CORPORATION OF WISCONSIN.

METAL BED.

No. 901,482.

Specification of Letters Patent.

Patented Oct. 20, 1908.

Application filed February 10, 1908. Serial No. 415,133.

To all whom it may concern:

Be it known that I, OTTO RUDD, a citizen of the United States, residing at Kenosha, in the county of Kenosha and State of Wisconsin, have invented certain new and useful Improvements in Metal Beds, of which the following is a specification.

My invention pertains to the joints of metal beds, such as those of the horizontal rails with the upright posts, or any others of a similar nature.

Heretofore, in joining the two pipes, tubes, bars, or the like together, it has been customary and usual to clamp a mold about the parts and then pour in molten metal, which when cool forms a union or enlargement encircling and fastening the two parts together. This chill casting or boss, frequently of a flower design, is objectionable because it forms a convenient place for the lodgment and retention of dust and dirt. It is also advantageous to do away with these enlargements because of the demand at the present time for bedsteads of extremely simple lines.

It is, therefore, the object of my invention to avoid the use of these uniting castings, in some cases unsightly, for the reasons specified, without diminishing or in any way sacrificing the strength and rigidity of the bedstead.

I have illustrated a number of embodiments of my invention on the accompanying sheets of drawings, forming a part of this specification, and on these drawings,—Figure 1 is a longitudinal section through one of the upright posts or pillars of a metal bed embodying my invention; Fig. 2 is a side elevation of the end portion of a rail of the same bedstead; Fig. 3 illustrates the appearance of the joint between the two parts shown in Figs. 1 and 2; Fig. 4 is a horizontal section through the joint illustrating its internal construction; Fig. 5 is a longitudinal section of a modified form of post; Fig. 6 is a similar section of a different style of rail for use in conjunction with the pillar or post shown in Fig. 5; Fig. 7 illustrates the appearance of the completed joint in which the two parts shown in Figs. 5 and 6 are firmly united; Fig. 8 is a horizontal section through the joint illustrated in Fig. 7; Fig. 9 is a lengthwise section through a vertical post or pillar of modified form; Fig. 10 is a side elevation of the end portion of a rail

bar for use with the post or pillar shown in Fig. 9; Fig. 11 is a side elevation of the joint uniting the two parts shown in Figs. 9 and 10; Fig. 12 is a horizontal section just above the rail of the joint shown in Fig. 11; Fig. 13 is a longitudinal section of a still further modified form of post; Fig. 14 is an elevation of the end portion of a rail adapted for connection with the post shown in Fig. 13; Fig. 15 shows in elevation the union of the parts illustrated in Figs. 13 and 14; Fig. 16 is a section on line 16, 16 of Fig. 15, as viewed in the direction indicated by the arrows; and Fig. 17 is a horizontal section on line 17, 17 of Fig. 15.

Referring first to the embodiment of my invention illustrated in Figs. 1 to 4, inclusive, it will be noticed that the cylindrical tubular post 20 is provided on one side with a cylindrical aperture or hole 21 of the same diameter as and adapted to accommodate the end of the tubular rail or rod 22. That portion of the post 20 adjacent to the aperture 21 is provided with a thin, cylindrical, tubular lining 23 supplied opposite the aperture 20 or hole 21 with a depression or indentation 24 somewhat larger than the hole 21, as is clearly shown in Fig. 1. This depression forms between the lining 23 and the interior surface of the post 20 a cavity or recess 25. The hollow cylindrical rail 22, which, as stated above, is the same size as the aperture 21, is supplied near its end with a plurality of transverse holes 26 extended through its wall, and the rail is also supplied near its end with another aperture 27 through its wall. In order to unite the parts and form a tight joint between the post and rail, the end of the latter is inserted through the aperture 21 into the cavity or recess 25, and the holes 26 are so positioned in the wall of the rail that they will be within the cavity 25 after this insertion, while the aperture or hole 27 will be located outside of the post. Molten metal is then poured through the inlet hole 27, partially filling the interior of the rail 22, and flowing out through the holes 26 so as to fill the cavity 25. This body of metal 28, as is obvious, will have a head of substantial size within the cavity 25 which will be considerably larger than the hole 21, so that it can not be withdrawn therethrough. This metal is firmly fastened to the end of the rail, owing to that portion thereof which fills the holes 26. It is under-

stood, of course, that the two tubes or pipes may be placed in any position desired while the metal is being poured and is becoming hard, and it will be obvious that as soon as 5 the cooling of the metal occurs the rail will be firmly and securely joined to the post. It will be apparent that a bedstead with all the joints formed in this manner will be of extremely simple design, and at the same time 10 will possess adequate strength for all purposes.

In Figs. 5 to 8, inclusive, I have illustrated a modified form of joint, and in this embodiment the aperture or hole 29 of the post 15 30 is larger in diameter than the tubular rail 31. The post 30 is equipped, as in the other species, with a lining 32 depressed at 33 to form a cavity 34. The rail 31 is supplied at its end with holes 35 corresponding to the 20 holes 26 of Fig. 2. It has no hole, however, corresponding to the aperture 27. Within the rail and adjacent to its ends is inserted a plug or cap 36 which is employed to prevent the metal poured into the joint from 25 flowing along the rail 31. To form the joint the end of the rail or tube 31 is inserted centrally through the aperture 29 into the recess 34, the holes 35 in these positions of the parts being within the cavity. A mold is then 30 35 clamped about the two tubes or pipes and a body of metal 37 poured into the same, the metal flowing between the rail and the margin of hole or aperture 29 into the cavity 34 and filling the same. The mold is so 35 40 shaped that a neat boss 38 is formed around the rail 31 at the point where it enters the upright post. This body of metal 37, owing to the fact that the cavity 34 is larger than the aperture 29, has a head filling the cavity 40 45 and thereby preventing withdrawal of the body of metal and the rail which is also securely locked to the metal 37 because the latter fills the apertures 35 and the end of the rail to the extent permitted by the internal 45 50 cap or stop 36. This design of joint is not quite so severely plain as that of Fig. 3, but each of them has sufficient strength for all purposes.

The joint or connection illustrated in Figs. 50 9 to 12, inclusive, is somewhat similar to that of Fig. 7, but in this instance the square rail 39 is solid and has one or more apertures or holes 40 extended through its end. The hollow boss 41, which may be of any desired 55 shape or contour in cross-section, has through one face an aperture 42 greater than the cross-section of the rail 39, and the post is also supplied, as in the other instances, with a lining 43 equipped with a depression 44 opposite the hole 42 to limit and restrict the flow of metal into the post. The end of the rail is inserted centrally in the aperture 42 and is pushed in far enough so that the hole or transverse aperture 40 of the rail is within 60 65 the cavity between the depression 44 and the

interior surface of the post. A mold of suitable shape is clamped about the parts and the metal poured in as described above, the mold being so shaped as to produce a boss 45 around the end of the rail and next to the 70 post or pillar.

I have shown in Figs. 13 to 17, inclusive, another style of joint in which the post 46 and the rail 47 are both hollow and rectangular in cross-section. One side wall of the 75 post has a hole 48 extended therethrough, the hole being larger than the cross-section of the rail, and the lining 49, which has a depression or indentation 50, is of substantially U-shape in cross-section and does not pass 80 completely around the interior surface of the post. The end of the rail has one or more holes 51 extended through its walls, and the interior of the rail, as in the case of the rail shown in Fig. 6, is equipped with an 85 internal plug or stopper 52 to limit the flow of metal into the rail. A mold is clamped about the two parts, as in the case of the joint shown in Fig. 7, and the finished joint has a boss or enlargement 53 about the end 90 of the rail.

In each of these cases it will be observed that the body of anchoring metal has a rather large head within the pillar or post whereby to secure a firm and rigid connection therewith, the metal being secured to the end of the rail by filling the apertures of the latter.

Although I have shown and described a number of forms of joints, each of which 100 embodies my invention, these are merely suggestive of a considerable number of such joints which would fall within the spirit and essence of my invention. It is, therefore, to be understood that my invention is not limited to the precise structural details shown and described, but is susceptible of a variety of embodiments, and that many minor mechanical changes may be made in the joints shown and described without departure from 105 the substance of my invention or the sacrifice of any of its benefits and advantages.

I claim:

1. In a joint for a metallic bed or the like, the combination of a hollow post or tube 115 having an aperture through its wall, a lining within said tube having a depression or indentation opposite said aperture, a rail or the like having an end inserted through said aperture into the recess formed by said depression, and a body of anchoring metal filling said recess and surrounding the end of said rail, substantially as described.

2. In a joint for a metallic bed or the like, the combination of a hollow post or tube 125 having an aperture through its wall, a lining in said tube having a depression or indentation opposite said aperture, a rail having an under-cut portion at its end, said end extending through said aperture into the recess 130

formed by said depression or indentation, and a body of metal in said recess surrounding and coöperating with the under-cut end of said rail, substantially as described.

- 5 3. In a joint for a metallic bed or the like, the combination of a hollow post or tube having an aperture through its wall, a lining in said tube having a depression or indentation opposite said aperture, a rail having a transverse aperture or hole at its end, said end passing through the aperture of said post into the recess formed in said post by the depression or indentation of said lining, and a body of metal filling said recess 10 and the aperture in the end of said rail, substantially as described.

4. In a joint for a metallic bed or the like, the combination of a hollow post or tube having an aperture through its wall, a lining in said tube having a depression or indentation opposite said aperture, a rail or the like the end of which is of less cross-section than and fits in said aperture and the recess formed by the depression or indentation of said lining, and a body of metal surrounding the end of said rail in said recess and filling the remainder of said aperture, substantially as described.

5. In a joint for a metallic bed or the like, the combination of a hollow post or tube having an aperture through its wall, a lining in said tube having a depression or indentation opposite and larger than said aperture, a rail or the like the end of which is of less cross-section than and fits in said aperture and the recess formed by said depression or indentation, and a body of metal surrounding the end of said rail in said recess and filling the remainder of said aperture, substantially as described.

6. In a joint for a metallic bed or the like, the combination of a hollow post or tube having an aperture through its wall, a lining in said post or tube having a depression or indentation opposite and larger than said

aperture, a rail or the like having at its end a hole or recess, said end of said rail being of less cross-section than and fitting in said aperture and recess formed by said depression or indentation, and a body of metal surrounding the end of said rail in said recess, and filling the remainder of said aperture and the hole or recess in the end of the rail, substantially as described.

7. In a joint for a metallic bed or the like, the combination of a hollow post or tube having an aperture through its wall, a lining in said tube having a depression or indentation opposite said aperture, a rail or the like the end of which is of less cross-section than and fits in said aperture and the recess formed by said depression or indentation, and a body of metal surrounding the end of said rail in said recess, filling the remainder of said aperture, and forming a boss around said rail outside of said post or tube, substantially as described.

8. In a joint for a metallic bed or the like, the combination of a hollow post or tube having an aperture through its wall, a lining in said tube having a depression or indentation opposite and larger than said aperture, a hollow rail or the like having one or more transverse holes through its end, the end of said rail being of less cross-section than and fitting in said aperture of the post or tube and recess formed by said depression or indentation of said lining, a body of metal surrounding the end of said rail in said recess, filling the remainder of said aperture, filling the transverse hole or holes of said rail, and forming a boss around said rail outside of said post or tube, and a stopper in said rail to limit the flow of said body of metal in said rail when the former is in a molten state, substantially as described.

OTTO RUDD.
